UNITED STATES PATENT OFFICE.

CHARLES M. HEETER, OF BUTLER, PENNSYLVANIA.

OIL-WELL DERRICK.

Application filed March 2, 1922. Serial No. 540,432.

To all whom it may concern:

Be it known that I, CHARLES M. HEETER, a citizen of the United States, residing at Butler, in the county of Butler and State of Pennsylvania, have invented a new and useful Improvement in Oil-Well Derricks, of which the following is a full, clear, and exact description, reference being had to the accompanying drawings, forming part of this specification, in which:

Figure 1 is a perspective view of a portion of a derrick constructed in accordance with the present invention;

Figure 2 is a detail sectional view on an enlarged scale illustrating a portion of the derrick;

Figure 3 is a transverse sectional view through the construction illustrated in Figure 2; and

Figure 4 is a view, corresponding to Figure 3, but illustrating a slightly modified form of construction.

The present invention relates broadly to building constructions, and more particularly to wooden tower structures, such as oil well derricks and the like.

It has heretofore been customary to construct oil well derricks by securing all of the parts in position with ordinary bolts. This requires drilling bolt holes through comparatively narrow pieces and in many cases adjacent the edge of other pieces. Such openings have frequently resulted in splitting of the respective pieces, thereby correspondingly weakening the entire structure. Furthermore, with such constructions accurate alignment of all of the openings is required thereby making the assembling operation a tedious one.

Frequently it is desired to knock down derricks of this nature and assemble them in other places. Experience has shown that where the parts are bolted together throughout with straight bolts, the removal of the bolts is extremely difficult due to the fact that they rapidly become oxidized and rusted in place.

In accordance with the present invention, the use of a large number of ordinary bolts is eliminated and there are substituted therefor U-bolts adapted to span certain pieces in the construction, thereby obviating the necessity of drilling the same. This makes the derrick easier to assemble, easier to knock down, and strengthens the entire structure. Referring more particularly to the draw-

ings, there is illustrated a portion of a derrick comprising four main corner structures A, each consisting primarily of substantially vertically extending sectional members 2 and 3 with broken joints arranged at approximately right angles to each other. The pieces of each corner structure are firmly clamped in place by U-bolts 4, adapted to straddle the pieces 3 on opposite sides of the joints, and having one leg extending through the pieces 2. Cooperating with the outer ends of the leg of each U-bolt may be provided a clip or washer 5 adapted to be engaged by the clamping nuts 6 for drawing and holding the members 2 and 3 in position.

The corner structures thus assembled, are in turn held in proper cooperative relation by transversely extending girts 7, the ends of which are engaged by angle irons 8, through which extend bolts 9 of usual construction. Intermediate the girts 7 may be provided diagonally extending reinforcing braces 10.

The sections forming the members 2 and 3 are cut to such lengths that the joints between sections will be located at approximately the center of one set of girts 7. Preferably, I cut these sections of such a length that each of the intermediate sections of the upright members 2 and 3 will extend from the center of one set of girts over the next set and to the center of the next set, as clearly shown in Fig. 1 of the drawings. This permits me to make relatively short sections of columns or corner forming members, also permits me to break the joints of the sections forming members 2 and 3 so that the joint between two sections of one member are reinforced by a section of the other member. As I preferably make the joints at the points where the girts are secured to the members 2 and 3, the joints between the sections of each member are not only reinforced by the other member but are also reinforced by the girts.

Where it is desired to provide a derrick of extra heavy construction, the sizes of the respective members constituting the corner structures may be increased as illustrated in Figure 4. In this figure the pieces 3' are clamped between the legs of the U-bolts 4', both of which extend through the piece 2'. In this construction there may be provided a clip or bearing 11 for the inner portion of the U-bolt to prevent the same from

being drawn into the piece 3', while a heavier clip 12, corresponding to the clips 5 already described, may be provided for the outer ends of the U-bolts.

5 In either form of the invention illustrated it will be apparent that the main portions of the structure are held in assembled relation by U-bolts which embrace the pieces 3 and 3', thereby obviating the necessity of 10 drilling bolt openings through these pieces. In this manner the original strength of the pieces 3' is conserved, and they are clamped in position in such manner that the entire structure may be readily knocked down as 15 desired. These constitute important advantages of the present invention.

I claim:

1. A derrick having a plurality of supporting columns, each column being formed 20 of two members at an angle to each other, each member being formed of a plurality of sections, the joints between the sections of one member being staggered relative to the

joints between the sections of the other member, and a U clamp on each side of each joint, said clamps straddling one member to clamp three sections of the two column forming members to each other, the one section of one member forming a reinforce for the ends of two sections of the other member. 25

2. A derrick having a plurality of supporting columns, each column being formed of two members at an angle to each other, each member being formed of a plurality of sections, the joints between the sections of one member being staggered relative to the joints between the sections of the other member, a plurality of sets of girts connecting the columns to each other, each joint of the column sections being overlapped by a girt, 30 and a U clamp on each side of each girt connecting the column members to each other. 35

In testimony whereof I have hereunto set my hand.

CHARLES M. HEETER.
